DESIGN FOR A CAKE OF SOAP OR THE LIKE

Frank McIntosh, New York, N. Y., assignor to Letheric Incorporated, New York, N. Y., a corporation of New York

Application August 24, 1937, Serial No. 71,296

Term of patent 7 years

To all whom it may concern:

Be it known that I, Frank McIntosh, a citizen of the United States, residing at New York city, in the county of New York and State of New York,
have invented a new, original, and ornamental Design for a Cake of Soap or the Like, of which the following is a specification, reference being had to the accompanying drawing, forming part thereof.

In the drawing:

Fig. 1 is a top plan of the cake of soap or the like showing my design; and

Fig. 2 is an end elevation thereof.

I claim:

The ornamental design for a cake of soap or the like, substantially as shown.

FRANK McINTOSH.
